UNITED STATES PATENT OFFICE.

GIANNI CAPRONI, OF MILAN, ITALY.

FLYING MACHINE.

1,420,620.

Specification of Letters Patent. Patented June 27, 1922.

Application filed May 14, 1920. Serial No. 381,309.

To all whom it may concern:

Be it known that I, GIANNI CAPRONI, a subject of the King of Italy, residing at Milan, Italy, have invented certain new and 5 useful Improvements in Flying Machines, of which the following is a specification, reference being had therein to the accompanying drawing.

This invention relates to flying machines 10 of the aeroplane class, more particularly multiplanes, and for illustration the invention is shown as applied to a pentaplane.

The general object is to so improve the system of construction, especially of pentaplanes, as to attain certain highly desirable 15 and essential advantages, namely simplicity of structure, and reduction of weight, and therefore the strains, to a minimum, yet preserving great strength and rigidity, 20 thereby minimizing the danger of injury or breakage. The further and more particular objects and advantages of the present invention will be elucidated in the hereinafter following description of one form or embodiment thereof or will be apparent to those 25 skilled in the art.

The main body of the aeroplane may be considered as comprising on each of its 30 symmetrically opposite sides a number of sections or trellis spaces, of which two are herein shown, although more would give a greater width of machine. The space within each trellis or section may be considered as divided by the superposed planes or wings 35 into a top or superior cell, a bottom or inferior cell, and at least one intermediate cell, or in the case of a pentaplane, two. The present invention has to do with the building up of this structure or system of 40 cells and trellises by means of interconnecting members, as will be described, extending between the respective planes, or rather the frame-work within said planes, and with the arrangement, relation and mode of interconnection of these various elements.

In the accompanying drawings showing 45 one convenient form or embodiment of the present invention, Fig. 1 is a diagrammatic front elevation intended to show the principle or system of structure, this view omitting the wing surfaces and many details such as the structure and arrangement of the steering and control mechanisms, and the rudders and other rear parts.

Fig. 2 is a partial similar front diagrammatic view showing a modified arrangement or embodiment of the invention. 55

Fig. 3 is a perspective view of a sufficient portion of the pentaplane shown in Fig. 1 to indicate the relation and interconnection of 60 the various structural members.

Fig. 4 is a partial side elevation.

The framework or structure within the several wings or planes is indicated diagrammatically at 11, 12, 13, 14 and 15 in Fig. 1, 65 and these references may be considered as pertaining more particularly to the longitudinal members or beams of the framework, of which there may be one near the forward edge and another near the aft edge of each 70 wing. The entire interior structure is unnecessary to illustrate, and would confuse the drawings. In Fig. 3 are indicated in dotted lines, the superior wing or plane 16 and those successively beneath it, 17, 18, 19 75 and 20, the last being the bottom or inferior wing or plane, and the five being spaced apart in proper relation according to any convenient principles of arrangement.

A fuselage or nacelle 21 is shown, carrying a motor 22 and tractor propeller, 23; and obviously these elements may be duplicated or variously modified. Underneath the planes is any desired structure, for landing on water or land; for example the landing chassis 25 is shown, connected to the main portion of the machine by a system of struts 26 and 27. The axle 28 carries the usual pneumatic wheels 29. 80

At the central portion or nucleus of the 90 machine a rigid structure of interconnected members may be afforded as follows. Near the center and spaced apart from each other are the rigid upright bars or struts 31, 31. These may be separate bars extending collectively the full height of the machine, and jointed to each other and to the five wing frames or longitudinal beams 11, 12, 13, 14 and 15; or the five may be rigidly united 95 into a single rigid upright. Between the opposite rigid uprights 31, and interconnecting them with the wing frames, are shown a series of tension members or cables. Thus, the diagonal cables 34 extend from the center of beam 12 to the junctions of beam 100 11 with the uprights 31. The cables 35 in the next lower cell are substantially continuous of the cables 34. A similar arrange- 105

ment of cables 36 and 37 is shown in the lowest two cells of the nucleus.

The subject of the remainder of the description, being symmetrically equivalent at the two sides, will for convenience be described only at one side. The opposite side will be understood to be the same. Also, while the diagram, Fig. 1, indicates only a single interconnecting member at each position, it will be understood that there will be at least two, that is, one near the forward and one near the rear edge of each plane. The space between each upright and the corresponding one to the rear of it may obviously contain interconnecting braces if desired, or may be covered with a suitable surface, so that a true cellular construction of aeroplane is afforded.

A series of rigid uprights or struts may be considered as dividing the system of superposed planes into trellises or cells. Thus, at each side of the center, and spaced well out from the nucleus, is shown at each side an upright rigid bar or bars 32 similar to the uprights 31, and forming between 31 and 32 the first trellis. A second trellis is shown, being comprised between the uprights 32 and a third similar upright 33 spaced still further from the center. The three rigid uprights 31, 32 and 33 at each side firmly unite the five planes into a solid strong structure.

These uprights may be constructed of hollow metal or of wood in a known manner and having, in cross section, an advantageous contour or streamline to minimize resistance as the member cuts through the air.

The most characteristic feature of the present invention consists in a special construction of bracing and strengthening wherein each of the extreme, that is the superior and inferior, cell rows, by which I mean the interplane spaces between the planes 1 and 2, on the one hand, and the planes 4 and 5 on the other hand, are rigidified and strengthened by a truss system independent of the general strengthening interconnections of the entire machine. I have thus provided two independent but cooperative systems of bracing, and these are arranged in such manner that the resulting stresses will have an offsetting effect tending to balance each other and thus minimizing the eventual strain and the tendency to injury or breakage.

Thus, referring to the lowest cell row, that is the space between the lower two planes 19 and 20, it will be observed that I have provided a plurality of rigid secondary uprights 41 spaced from each other, extending between the frames 14 and 15, and located between the main uprights 31 and 32. Again similar secondary uprights are shown between the main uprights 32 and 33. The

truss structure may be simply and effectively completed by means of rigid diagonals 42 each extending from the intersection of the upright 41 with one of the frames, to the intersection of the main upright with the other of the frames. This light strong structure, carried the entire width of the machine, between the frames 14 and 15, suffices to substantially convert the lowest cell row into a rigid elongated truss. The superior cell row, between the frames 11 and 12, is shown as similarly trussed by rigid secondary uprights 43 and diagonals 44.

Cooperating with the described bracing system, I have shown, for each trellis space, a general bracing system extending from the superior to the inferior plane. This is shown as effected by what may be termed the main diagonal cables 46, 46 extending from corner to corner of each trellis and suitably united, if desired, with each of the planes intersected by the cables, especially the middle frame 13, at 47.

An equivalent structure is indicated in Fig. 2 wherein the arrangement is generally the same, but the number of short or secondary rigid uprights 48 within each trellis space is increased to four and the short rigid diagonals are replaced by crossed tension members or cables 49 within each sub-divided cell.

The effect of either described construction, or other equivalents embodying this invention, affords special advantages, resulting in minimizing the stresses created in the machine under the influence of air pressure. If we ignore the elements of truss structure in the superior and inferior cell rows, it will be perceived that the effect of upward air pressure will tend to exert an action of compression in the topmost or superior wing or plane 11 and an action of tension in the inferior plane 15. If we now consider the truss structures between the frames 11 and 12, and between frames 14 and 15, these being inter-united with each other and with the middle plane 13 by the rigid uprights 31, 32 and 33, it will be observed that the tendency in the superior plane is to the creation of tension, and in the inferior plane compression. These two sets of forces thus tend to a substantial extent to counterbalance and offset each other, thus materially reducing the resulting stress, and minimizing the strains imposed on the planes and structural members. In this way a considerable reduction of weight is permitted, which in turn effects a further reduction of stress. I do not deem it necessary to completely expound the theory of the stresses involved, but from the explanation given it will be seen that in practical use the present invention accomplishes, to a large degree, the objects and advantages previously recited.

In addition to the features specifically claimed hereinbelow are broader features made the subject of claim in applicant's co-pending application Serial No. 381,307, filed

5 May 14, 1920.

Since certain matters of arrangement, form and detail may be modified without departing from the principles involved, it is not intended to limit the present invention

10 to such features, except in so far as set forth in the appended claims.

What is claimed is:

1. A multiplane of four or more superposed planes having spaced apart uprights 15 each connected to the frames of all the planes; and, extending between the upper two planes, a truss system comprising such uprights and diagonal brace members giving unitary rigidity to the combined upper two 20 planes, and between the lower two planes such a truss system giving unitary rigidity to the combined lower two planes, and a separate means bracing the entire system of planes comprising a system of long diagonal 25 tension members extending from the topmost to the lowermost frames.

2. A pentaplane having its five superposed planes, spaced apart rigid uprights connecting the frames of all the planes and forming trellis spaces of four superposed cells, 30 general diagonal stay members extending across each trellis from the topmost to the lowermost frames giving a truss bracing to the entirety, supplemental interplane trussing within the several superior cells such as 35 to constitute a rigid truss of the upper two combined frames, and such interplane trussing within the inferior cells to constitute a rigid truss of the lower two combined frames.

3. A multiplane having four or more superposed planes, opposite rigid uprights near the center, and braces between them constituting a nucleus, additional rigid uprights beyond said uprights, diagonal braces 45 rigidifying the whole, and bracing means between the first and second and between the last two planes to independently render them rigidly unitary.

In testimony whereof, I have affixed my 50 signature hereto.

GIANNI CAPRONI.
